VICTOR J. GOVER,
INVENTOR:

BY *Victor J. Gover*,

ATTORNEY.

UNITED STATES PATENT OFFICE

VICTOR J. GOVER, OF NEW HAVEN, CONNECTICUT

TENSION DEVICE

Application filed May 26, 1928. Serial No. 280,833.

This invention relates to improvements in tension devices for high speed braiding machines.

The primary object of the invention resides in a tension device for placing a tension on the braid or thread as it leaves the bobbin, and which bobbin will not permit the paying out of thread therefrom until the tension or pull on the thread reaches a pre-determined amount.

Another object is to provide a tension device for high speed bobbins by which the bobbin is prevented from idly spinning upon the decrease of a tension of a predetermined amount, or upon the accidental breaking of the braid or thread.

A further object is the provision of a tension device for bobbins which includes a vertically movable dog normally engaging the ratchet tooth surface on the top of the bobbin to prevent rotation of the same, which dog is under the control of suitable means by which it is lifted free of the ratchet tooth surface when the tension on the thread from the bobbin reaches a predetermined amount, the dog automatically dropping into engagement with the ratchet tooth surface upon the decrease of tension on the thread below a certain amount, whereby the bobbin may be instantaneously stopped in case of breakage of the thread.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a side elevation of my improved tension device.

Figure 2 is a front elevation thereof.

Figure 3 is a top plan view.

Figure 4 is a horizontal sectional view on the line 4—4 of Figure 2.

Figure 5 is a similar view on the line 5—5 of Figure 2.

Referring to the drawing by reference characters, the numeral 10 designates a bobbin bracket adapted to be removably mounted on a braiding or like machine, having a

spindle 11 rising therefrom on which a bobbin 12 is turnably mounted. The bobbin may be wound with a supply of thread or braid 13 which is adapted to be unwound therefrom during the operation of the machine of which it serves a part. The top of the bobbin is provided with an annular series of ratchet teeth 14 for a purpose to be hereinafter explained.

Cast integral with the attaching bracket or base 10 and rising therefrom, is a post or standard 15 which is elliptical in cross section as shown in Figure 5 of the drawing, while mounted in the base and in an ear 16 at the top of the post is a rod 17. The rod 17 is disposed in spaced parallel relation with respect to the post and co-acts therewith for slidably supporting a carriage 18. The carriage is in reality only mounted on the rod while spaced fingers 19 on the carriage embrace the sides of the post for preventing accidental turning movement of the carriage upon the rod.

A thread guide or eye 20 rises from the carriage through which the thread 13 passes after passing through an opening 21 in the post. After passing through the eye 20, the thread is carried up and passes through an opening 22 in the ear 16 from where it leads to the working parts of the machine.

Slidably mounted adjacent the top of the post is a head 23 which supports an inwardly extending dog 24, pivoted on a vertical axis to one side of the head as at 25 and which is held rigid thereagainst by a spring 26 fixedly carried by one side of the head. By pivoting the dog on a vertical axis, the same may be swung upon the release of the spring, to a position out of the vertical plane of the bobbin as shown in dotted lines in Figure 4 of the drawing, to facilitate the application of and removal of the bobbin to the spindle.

Depending from the head 23 is a bar 27 which lies close to the post and has an outwardly extending lug 28 on its lower end disposed in the path of upward movement of the carriage to be engaged thereby, while an ear 29 extends outwardly from the bar through which the rod 17 extends. An expandable spring 30 encircles the rod 17 and is interposed between the ears 29 and 16 for

normally holding the bar and head down with the dog 24 in operative position upon the ratchet teeth of the bobbin. A second expansion spring 31 encircles the rod between the carriage 18 and a collar 32 fixed to the rod below the lowermost position of the ear 29. The spring 31 acts upon the carriage to move the same down upon the bracket or base 10.

- 10 In practice, the free end of the thread or braid from the bobbin is threaded through the tension device in the manner described and shown, and as a pull is exerted thereon, the tension on the thread overcomes the tension on the spring 31, whereupon the carriage rises vertically and strikes the lug 28. Up until this time the bobbin has been locked against rotation by the dog and ratchet teeth, but as the carriage strikes the lug 28, it lifts 15 the bar 27, head 23 and dog 24, against the action of the spring 30 so that the dog is lifted free of the plane of the top of the bobbin so as to be out of the path of the ratchet teeth. The dog being in a raised position as shown 20 in dotted lines, a tension of a predetermined amount is necessary on the thread to maintain this position, at which time the thread may be evenly pulled from the bobbin. In the event that the tension on the thread should decrease by reason of slack therein, or by the breaking of the thread, the springs 30 and 31 will instantly return the parts to the position shown in full lines in the drawings, at 25 which time the dog drops into co-acting position with the ratchet teeth and brings the bobbin to an abrupt stop to prevent the unnecessary spinning of the bobbin and the waste of thread or braid which would be caused thereby.
- 30 This tension device is especially adapted for high speed braiding machines such as those used for braiding electric conductor wires, but, I do not wish to limit myself thereto, as it may be used in slow speed machines 35 and other types of machines than the type above mentioned.

40 While I have described what I deem to be the most desirable embodiment of my invention, it is obvious that many of the details 45 may be varied without in any way departing from the spirit of my invention, and I therefore do not limit myself to the exact details of construction herein set forth nor to anything less than the whole of my invention 50 limited only by the appended claims.

55 What I claim as new is:—

1. In combination with a supporting bracket having a spindle thereon, a bobbin rotatably mounted on said spindle, a series of 60 ratchet teeth on the top of said bobbin, a post rising from said bracket beside said bobbin, a head slidably mounted on said post, a dog pivoted to said head for swinging movement out of the vertical plane of said bobbin, a spring catch carried by said head for 65

holding said dog in the vertical plane of said bobbin for coaction with said ratchet teeth, a bar extending downwardly from said head, a fixed rod disposed parallel to said post, a carriage slideable on said rod and movable into the path of said bar to lift said dog out of engagement with said ratchet teeth, and spring means respectively acting to normally hold said dog in engagement with said ratchet teeth and said carriage in a lowered position, substantially as and for the purpose specified. 70

2. In combination with a spindle having a bobbin rotatably mounted thereon, ratchet teeth provided on the top of said bobbin, a vertical slideable member, a dog pivotally mounted on said member for swinging movement beyond the vertical plane of said bobbin, and a spring catch carried by said member and engaging said dog for locking said dog against swinging movement in a vertical plane with said bobbin for co-action with said ratchet teeth. 80

85 In testimony whereof I have affixed my signature.

VICTOR J. GOVER.
